(57) **CLAIM**

The ornamental design for a tire, as shown and described.

DESCRIPTION

FIG. 1 is a perspective view of a tire showing our new design;

FIG. 2 is a front view thereof;

FIG. 3 is a rear view thereof;

FIG. 4 is a top plan view thereof, for which the bottom plan view is the same;

FIG. 5 is a right side view thereof;

FIG. 6 is a left side view thereof;

FIG. 7 is an enlarged view taken along line 7-7 in FIG. 2; and, FIG. 8 is a cross-sectional view taken along line 8'-8' in FIG. 7.

In the drawings, the broken lines showing portions of the sidewall and inner bead depict portions of the tire which form no part of the claimed design.
